HOLSTER FOR A POLICE CLUB

Paul D. Starrett, Rindge, N.H., assignor to Monadnock Lifetime Products, Inc., Fitzwilliam, N.H.

Filed Oct. 21, 1974, Ser. No. 516,818

Term of patent 14 years

Int. Cl. D3—02

U.S. CL. D22—13

FIG. 1 is a front view of a holster for a police club, the broken lines showing a portion of a police club and belt for illustrative purposes only;

FIG. 2 is a back view;

FIG. 3 is a side view of FIG. 1 as seen from the right side;

FIG. 4 is a top view; and

FIG. 5 is a bottom view.

I claim:

The ornamental design for a holster for a police club, as shown and described.
